RAFT LAUNCHING DEVICE

Thomas W. Hooley, Jr., New Orleans, La.

Application May 26, 1942, Serial No. 444,562

4 Claims. (Cl. 9—22)

The invention relates to raft launching devices and has for its object to provide a device of this kind having trackways inclining downwardly and outwardly, and adapted to support and guide a life raft over the side of the ship and into the water.

A further object is to provide the raft on its under side with antifrictional rollers adapted to engage the under sides of the trackways for holding the raft in position on the trackways particularly as the ship rolls.

A further object is to form the trackways from angle irons and to provide the flanges of said angle irons, on which the raft rests, with recesses through which the outer rollers are received when the raft is placed on the trackways.

The recesses and inclined trackway also allow the raft to float clear of the vessel in case of sinking of the vessel, for instance when the vessel sinks rapidly when torpedoed.

A further object is to provide a tripping mechanism or frame between the trackways and pivotally mounted and adapted to engage the outer end of the raft for holding the same in position on the trackways. Also to provide means for holding said tripping frame against pivotal action until it is released for a raft launching operation.

With the above and other objects in view the invention resides in the combination and arrangement of parts as hereinafter set forth, shown in the drawing, described and claimed, it being understood that changes in the precise embodiment of the invention may be made within the scope of what is claimed without departing from the spirit of the invention.

In the drawing:

Figure 1 is a side elevation of the launching device.

Figure 2 is a front elevation of the launching device.

Figure 3 is a top plan view of the launching device.

Figure 4 is a sectional view taken on line 4—4 of Figure 1.

Referring to the drawing, the numeral 1 designates the side rail of a ship and over which the raft 2 is launched. It is the present practice to stack rafts on the upper decks of ships, and when launched a great deal of time is consumed, hence loss of life is increased incident to delay and the impossibility of launching the rafts, particularly when the ship is listing. In modern warfare merchant ships sink in a few minutes, hence there is no time to handle rafts. To obviate the

above difficulties the raft 2 is supported in an inclined position, shown in Figure 1 on spaced tracks 3 formed from angle iron, and on the flanges 4 thereof. The tracks 4 are supported by uprights 5 and by brackets 6 mounted on the rail 1. The under side of the raft 2, which may be of any construction, is provided with skids 3a which slide on the flanges 4, and secured to the inner sides of the skids 3 are brackets 7, provided with antifrictional rollers 8, which engage the under sides of the flange 4 for maintaining the raft positively on the trackways 3, and assisting in the downward sliding of the raft. It will be noted that the rollers also prevent outward displacement of the raft in relation to the trackways when the ship is rolling.

Rockably mounted in bearings of opposite uprights 5 is a shaft 9, to which is connected, by welding, at 10 a U-shaped latching member 11. The latching member 11 has its arms 12 upwardly disposed and adapted to engage the lower end of the raft for holding the same against downward movement on the tracks 3. A flexible member 13 is connected at 14 to the portion 15 of the latching member and extends downwardly and anchored to a shackle 16, preferably by means of a quick opening pelican hook 17, therefore it will be seen that when it is desired to launch the raft 2, the flexible members 13 may be released, and then the raft will slide downwardly on the trackways 3 into the water. It will be noted that the lower ends of the trackways 3 are sufficiently high in relation to the rail 1 so that the rollers 8 will clear the rail 1.

To facilitate the placing of the raft 2 on the trackways 3 the flanges 4 of the trackways are provided with interruptions 18, which receive the lower rollers 8 when the raft is hoisted by mechanism, not shown, and lowered onto the trackways. After the lower rollers 8 pass through the interruption 18 it will be seen that the raft skids, for the major portion of their length, will rest on the flanges 4, and the upper rollers will be above the upper ends of the flanges 4, but in position whereby when the raft is lowered by the hoisting mechanism, said upper rollers will pass below the flanges 4, and the raft will be held by the latching mechanism 11. The latching mechanism 11 is preferably provided with a stop lug 19, which engages the flange of one of the supports 5 for limiting the pivotal action of the latching member 11 so that its lower end will not be forced upwardly into engagement with the under side of the raft.

From the above it will be seen that a raft

cradling and launching device is provided which is simple in construction, positive in its operation, and one wherein the raft may be quickly launched without loss of time, particularly desirable in modern warfare where merchant ships are torpedoed.

When the vessel sinks it will be seen that the raft will float clear of the vessel. Under these conditions the front rollers will pass upwardly through the recesses 18 at which time the rollers 8 will be clear of the upper ends of the trackways.

The invention having been set forth what is claimed as new and useful is:

1. A raft cradling and launching device for ships, said device comprising spaced downwardly and outwardly inclined trackways, said trackways being formed from angle bars and adapted to receive therein the under side of a life raft in a position whereby said raft will slide on one of the flanges of the trackways, said last named flanges having interruptions intermediate their length and rollers carried by the under side of the raft and engaging the under side of the

trackway flange, one of said rollers being receivable through the interruptions of said flanges.

2. A device as set forth in claim 1 wherein said interruptions are positioned for the reception of the rollers at one end of the raft when the rollers at the other end of the raft are above said interruptions and in a plane below the plane of the flanges.

3. A device as set forth in claim 1 including a pivoted latching member pivoted below the trackways and extending into the path of the lower end of the raft.

4. A device as set forth in claim 1 including a pivoted latch pivoted below the spaced trackways and extending upwardly between the trackways and into the path of the raft means for holding said latching member against pivotal action when in engagement with the end of the raft, means for releasing said latching member and means for limiting the pivotal action of the latching member.
